DESIGN FOR A ROLLING CIGARETTE CASE

Joseph Halpern, New York, N. Y.

Application November 20, 1943, Serial No. 111,750

Term of patent 3½ years

To all whom it may concern:

Be it known that I, Joseph Halpern, a citizen of the United States of America, residing in New York city, county of Bronx, and State of New York, have invented a new, original, and ornamental Design for a Rolling Cigarette Case, of which the following is a specification, reference being had to the accompanying drawing, forming part thereof, wherein,

I claim:

The ornamental design for a rolling cigarette case, substantially as shown.

JOSEPH HALPERN.
